WASTE AND VENT FITTING

Filed Sept. 28, 1928

Inventor:

Joseph J. Crotty

By his Attorney

Clarence B. Kerr

UNITED STATES PATENT OFFICE

JOSEPH J. CROTTY, OF NEW YORK, N. Y., ASSIGNOR TO THE CENTRAL FOUNDRY COMPANY, OF NEW YORK, N. Y., A CORPORATION OF MAINE

WASTE AND VENT FITTING

Application filed September 28, 1928. Serial No. 308,934.

My invention relates to waste and vent fittings and comprises a novel combination of fittings the important ones of which in themselves are also new, which provide a simple and compact arrangement constructed to give the maximum efficiency with a small number of parts. To this end my improved fittings and combinations provide waste and vent connections with a number of fixtures such as bathtubs, sinks, basins and toilets by which the waste is discharged into the waste stack and they are at the same time vented through a common vent stack. My improved fittings are formed and connected so as to avoid, as completely as possible, sharp angles or abrupt changes of direction, and thus prevent clogging of the fittings or siphoning of the fixtures.

My invention also comprises features which I shall hereinafter describe and claim.

In the accompanying drawing the figure is an elevation of an arrangement of fittings embodying my invention.

Referring more particularly to the drawing, I have shown my invention applied to a frame of fittings connected to the main soil or waste stack A and having a main vent connection B. The fitting 2, which is inserted into and forms a continuation of the soil stack A, has the usual vent and toilet connections 3 and 4, and also a laterally projecting waste connection 5, which runs into the enlarged portion 6 of the fitting 2 below the connection opening 4 for the toilet C, and extends outwardly at an angle of about 45°, preferably terminating in the hub 7. Caulked into the hub 7 is the angled lower end 8 of horizontal waste member 9, which has vertically angled branches 10 and 11 and horizontally angled branches 12 and 13. The branches 10 and 11 are angled at approximately 45° so as to provide a sweep for the flow of any waste down through these branches and eliminate the usual right angled connection. I have shown the branches 10 and 11, caulked in, respectively, the angled lower ends 14 and 15 of the vertically disposed members 16 and 17. The member 16 is provided with a connection 18 for a sink or basin D, and in its lower portion acts

as a waste member and in its upper as a vent member, while the member 17 acts as a vent. Into the upper ends of the members 16 and 17 are preferably caulked the downwardly projecting branches 19 and 20 of the vent pipe 21, which leads through the upper end of the toilet vent 22 to a connection B, which may be part of the vent stack. Either of the branches 12 and 13 may be connected to a bathtub E or other fixtures, and are vented by the member 17.

It will be seen that any water running down the vertically disposed member 16 from the basin D will be diverted from a vertical flow through its angled end 14 into the aligned branch 10 and thence into the horizontal waste member 9. From there it will flow through its angled end 8, and through the portion 5, which is aligned with the end 8, into the enlargement 6 and on into the soil stack A.

Constructing the lower ends 14 and 15 of the member 16 and 17 in alignment with the branches 10 and 11 will cause the waste water to sweep down to the member 9 in such manner that it will be forced toward the end 8 of that member, and waste water will be prevented from running toward the fixture E and its trap e, which otherwise is apt to fill gradually and clog with sediment. The sweep of the water carries it through the member 9, and from there it is carried in a straight run through the end 8 and the aligned connection 5 to the stack. The changing of the course of the waste water from a vertical run to a horizontal and then back to a vertical run is thus effected without abrupt change of direction and with a minimum of disturbance. By so doing there is little opportunity of creating water surges or of trapping air, all of which frequently causes clogging of the waste members and even of the stack, or the siphoning of the fixtures, all of which cause annoyance, interruption of service and frequent damage.

While I have shown the various fittings embodying my invention with caulked joints, it is obvious that various types of joints may be satisfactorily used with my improved fittings.

The terms and expressions which I have employed are used as terms of descriptions and not of limitation, and I have no intention, in the use of such terms and expressions, of excluding any mechanical equivalents of the features shown and described, or portions thereof, but recognize that various structural modifications are possible within the scope of the invention claimed.

10 What I claim is:

- 11 1. In a waste and vent system a unitary horizontal fitting having an angled end adapted to cooperate with an angled extension of a vertical waste stack, a bell at its opposite end in communication with the discharge from a plumbing fixture and a plurality of intermediate branches extending throughout their lengths at an acute angle to the axis of the fitting and having their end faces at a complementary angle to said axis, and vertically disposed vent and waste pipes having angled lower ends adapted to co-operate with said branches, the arrangement being such that water discharged into said waste pipe and air drawn through said vent flow freely without abrupt changes in direction into said waste stack.
- 12 2. In a waste and vent system a frame comprising a horizontal fitting and a plurality of vertical pipes, said pipes being in communication at their upper ends with a vent stack, said fitting having branches intermediate its ends extending at an acute angle throughout their length to the axis of said fitting, said pipes having angled lower ends connected directly with said branches, one end of said fitting being angled for connection with an angled extension of a waste stack, and connections for discharging waste water from plumbing fixtures into the opposite end of said fitting and into one of said pipes.

In testimony whereof, I have signed my name to this specification this 25th day of September, 1928.

43 JOSEPH J. CROTTY.
